[57] CLAIM

The ornamental design for a trailer jack foot, as shown and described.

DESCRIPTION

FIG. 1 is a perspective view of a trailer jack foot showing my new design;

FIG. 2 is a side elevational view, the view from the opposite side being a mirror image thereof;

FIG. 3 is a top plan view;

FIG. 4 is a front elevational view; and,

FIG. 5 is a rear elevational view.

The bottom of the trailer is flat and unornamented.

FIG. 5

FIG. 1

FIG. 3

FIG. 2

FIG. 4
